AIR PURIFIER

Robert John, New York, N. Y.

Application June 25, 1934, Serial No. 732,331

12 Claims. (Cl. 219—39)

This invention relates to improvements in air purifiers of the mechanically operated type and has among its objects to provide a novel fan structure whereby to move large volume of air at a relatively low power expense without creating violent horizontal drafts such as are produced by the conventional rotary fans of the prior art; another object of the invention is to treat the air flowing through the fan mechanism in such a way as to destroy both odors and germ life, whereby the air of a closed room may be subjected to a continuous process of deodorization, sterilization and ionization.

Other objects and advantages of the invention will appear in the following description of the preferred embodiment of my invention shown in the attached drawings of which:

Figure 1 is a perspective view in elevation of the device;

Figure 2 is a horizontal cross-section on the line 2—2 of Figure 1 looking upwardly;

Figure 3 is a vertical cross-section on the line 3—3 of Figure 1;

Figure 4 is a horizontal cross-section on the line 4—4 of Figure 1 looking downwardly; and

Figure 5 is a view similar to Figure 2 showing a modification of the air purifier including an air activator.

Referring more particularly to the drawings, 10 indicates a base, 11 indicates the horizontally disposed fan, 12 indicates a heating element for purifying the air, and 13 indicates the windstream control element.

As shown in Figure 3, the base 10 is of hollow formation and includes a bottom member 14 to which is secured a plurality of legs 15, preferably made of rubber, felt, or other sound-absorbing material, so as to minimize transmission of sound and avoid scarring of furniture. The sides 16 of the base 10 extend upwardly and inwardly to form a motor chamber in which is positioned a fan motor 17. This motor may be any conventional type of electric fan motor capable of running with its shaft 18 vertically disposed. Preferably, the shaft 18 is provided with a ball thrust bearing 19 mounted upon the central portion of the bottom member 14.

The fan 11 is secured to the upper portion of the shaft 18 for rotation therewith and, as shown, its blades are horizontally disposed. Fan casing 20 is supported by the walls 16 of the base 10 by means of supporting members 21 riveted or welded to the walls 16 and to the periphery of the fan casing 20. The fan casing is preferably provided with an upstanding perforated wall 22

surrounding the fan blades and is preferably provided with a wire mesh bottom portion 23 of annular formation.

The windstream control member 13 consists of a completely enclosed thin metallic shell somewhat acorn shaped and is supported directly above and concentric with the fan by means of extensions 24 of the supports 21. The contour of this shell presents a surface 25 curving outwardly and upwardly over the tips of the fan blades and a surface 26 curving inwardly above the point 27 of its greatest diameter. Surface 26 presents a compound curve in cross-section, as shown in Figure 3, and preferably terminates in a point 28 at its upper end.

The air purifier element 12 is secured to the bottom of the windstream control element 13 directly above the fan 11. In the modification shown in Figures 1 to 4, inclusive, the purifier element comprises a refractory block 29 which is grooved for the reception of a heating element 30.

Both the heating element 30 and the motor 17 are supplied from the same source of power by a lead 31 and a switch 32 is mounted upon the inside of the wall 16 of the base member 10 for connecting or disconnecting the motor and heating element. The switch 32 may have an operating member 33 projecting outwardly through an aperture in the wall 16.

By way of explanation of the operation of my windstream control member 13, I call attention to United States Patent No. 1,064,524, issued June 10, 1913 to Nelson and Ruggaber, as illustrative of a horizontal fan of the prior art. It will be observed that the operation of this fan creates a radial air draft, in contradistinction to which, the purpose of my improved structure is to reduce to a minimum any radial draft, and to confine my draft to a narrow upward stream, whereby the air inlet beneath the fan is affected to the least possible extent by the air being discharged from fan, in order to promote the free flow of air through the mechanism. If a lighted candle be held as far as four feet, horizontally, away from a fan of the type of Nelson and Ruggaber, the air being discharged from said fan radially will bend the flame away from the fan, or even extinguish it; if a lighted candle be held two feet directly above the center of said Nelson and Ruggaber fan, there is no apparent deflection of the flame, nor is any draft observed. Under comparative conditions as to fan blade contour, size and speed, it has been observed that in my improved structure the candle flame shows no radial discharge of air when held as close as three inches away.

from the tips of the fan blade. On the other hand, the air currents at all points from top to bottom of the mechanism are observed to be inward. Also, if the lighted candle be placed directly above the center of my windstream control member 13, the flame will be promptly extinguished, the greatest intensity of air movement apparently being directly over the point 28 of the member 13. This characteristic has been further verified by anemometer tests. The reason for this directional control of the air currents will be obvious when it is considered that the air discharged by the tips of the fan blade first strikes an upwardly rounded surface which causes it to wipe, upwardly, the contour of windstream control member 13 causing a reduction in pressure inwardly of said air stream, between it and the surface 26, whereby the upwardly traveling stream of air is bent inward and follows quite closely the contour of said acorn-shaped member 13, creating an upward stream, free from radial currents, obviating sharp horizontal drafts in the room, and preventing turbulence which might interfere with the free flow of the air to the intake side of the fan.

It has been observed that by maintaining the resistance element 30 at cherry red while the fan is in operation, the temperature of the resistance wire itself is at approximately 1000° F., and the temperature of the air directly below the heating element, that is, between the heating element 12 and the blades of the fan 11, is at a temperature of from 300° F., to 350° F., while the temperature at the apex of the air stream, several inches above the point 28 is approximately that of the room, or possibly a degree or so lower. The point 28 is made of a heat conductive metal and is bathed by the air stream and may be at a temperature of 10° F., to 12° F., above the temperature of the room.

As indicated above, the temperature of the air a few inches above the point 28 has been consistently observed to be approximately that of the temperature of the air entering the device, that is, the temperature of the air of the room. In fact, an accurate thermometer placed in the air at the point described will consistently read approximately 1° F., lower than the same thermometer placed in the air entering the device, although calculations taking into account the energy consumed by the heating element, the rate of air flow and the specific heat of air, indicate that the temperature of the air leaving the device should be several degrees higher than the temperature of the entering air. It is to be observed, however, that the air in passing through the fan mechanism has been subjected to a temperature sufficient to be destructive to germ life and to destroy certain volatile odors, and that this air is redelivered to the room at a temperature as low as, or lower than that at which it originally entered the fan mechanism. Further, it has been subjected to ionization resulting from violent temperature changes, contact with red hot metal, and possibly to the vaporization and reabsorption of its moisture content, all of which steps are known to affect the molecular structure of the oxygen of the air to produce a more rapid rate of oxidation of substances in contact therewith than that of unheated, un-ionized, atmospheric oxygen. Also, the heat of the red hot resistance wires is sufficient to effect combustion of carbon monoxide and other incompletely oxidized carbonaceous compounds.

As a modification of my air purifier, I show in

Figure 5 a similar structure in which the heating element described is omitted and in its place there may be substituted an air activator or ozonizer 34 (Figure 5) of the type described in my co-pending United States patent applications No. 623,227 and No. 585,101, or ozonizers or ionizers of the prior art. The air activator 34 may comprise a dielectric plate 35 surrounded by a metallic rim 36 secured to a metallic element 37 affixed to the bottom of the windstream control member 13. An outer electrode 38 in contact with the metallic rim and an inner electrode 39 may be secured to opposite sides of the dielectric plate. The inner electrode 39 is connected by a lead 40 to one high voltage terminal of a step-up transformer (not shown) positioned within the windstream control member and having its other high voltage terminal grounded to the windstream control member. Such an air activator produces a silent electrical discharge the operation of which is to destroy odors, germ life, and to ionize the air stream to a degree comparable with that produced by the naked cherry red heating wires above described.

My invention, I believe, will be found particularly useful in homes, offices, hospitals and public halls, and wherever portable rotary fans are now employed. Its advantages over the portable rotary fans of the current art are (1) that it creates no drafts such as are likely to induce colds, blow papers about, or stir up dust, but minus these defects it moves sufficiently large volumes of air to have a cooling effect on the bodies of persons in the room; and (2) it purifies the air in the process of moving it.

In the embodiment of my invention chosen for the purpose of exemplification, I have described an air purifier by means of which a continuous stream of air is subjected to a temperature of 300° F., or more, and redelivered at room temperature or less; such a balance between heat input and air flow is desirable where the apparatus is to be used merely for air purification in rooms heated by independent means; obviously, by maintaining the naked wires of my device at white heat, as by increasing the electrical input, or decreasing the rate of air flow, it is possible to employ the apparatus for warming the air of the room, as well as purifying it. Such modifications necessary to produce any desired result are well known to those skilled in the art; also, by varying the pitch and contour of my fan blades and by altering the curved surfaces of my acorn-shaped windstream control according to the principles of published engineering data available to all, the directional control of the air stream may be varied to produce wider or narrower upward air stream columns. These and many other modifications of my invention may be made without departing from the scope of the invention as described and claimed herein.

I claim:

1. An air moving mechanism comprising a rotary fan and an air deflector spaced apart therefrom, said air deflector having an imperforate surface presented toward said fan and being curved outwardly from said fan near its widest diameter and inwardly toward the axis of said fan from its widest diameter to the point in its contour farthest away from said fan whereby the air from said fan flows around the outer surface of said deflector.

2. An air moving mechanism comprising a rotary fan and an air deflector spaced apart there-

from, said air deflector having an external surface presented toward said fan and being curved outwardly from said fan near its widest diameter and inwardly toward the axis of said fan from its widest diameter to the point in its contour farthest away from said fan whereby the air from said fan flows around the external surface of said deflector, said curvature beyond said widest diameter comprising compound curves.

10 3. An air moving mechanism comprising a rotary fan and an air deflector spaced apart therefrom, said air deflector having an external surface presented toward said fan and being curved outwardly from said fan near its widest diameter and inwardly toward the axis of said fan from its widest diameter to the point of its contour farthest away from said fan whereby the air from said fan flows around the external surface of said deflector, said inward curves meeting at a point farthest from said fan.

15 4. An air moving mechanism comprising a rotary fan and an air deflector, said deflector having an external surface presented toward said deflector spaced apart therefrom whereby the air from said fan flows around the external surface of said deflector, some portions of said deflector adjacent said fan being sloped away therefrom and other portions of said deflector more distant from said fan being sloped in an opposite direction.

20 5. In combination, an air purifying mechanism comprising a rotary fan, an electrical resistance heating element spaced apart therefrom and exposed directly to the air coming from said fan, and means for maintaining said electrical resistance heater at red heat when said fan is in operation.

25 6. In combination, a rotary fan positioned to produce an upwardly directed current of air, and a single deflector positioned within said current and axially thereof for maintaining the upward direction of said air current.

30 7. In combination, a rotary fan positioned to produce a current of air having a generally upward movement, and a single windstream control member positioned axially within said cur-

rent to minimize horizontal currents of air normally produced by said fan.

35 8. In combination, a rotary fan positioned to produce a current of air having a generally upward movement, a single windstream control member positioned axially within said current to minimize horizontal currents of air normally produced by said fan, and an air purifier positioned to contact said air between said fan and said control member.

40 9. In combination, a rotary fan positioned to produce a current of air having a generally upward movement, a single windstream control member positioned axially within said current to minimize horizontal currents of air normally produced by said fan, and an air purifier comprising a heating element positioned to contact said air between said fan and said control member.

45 10. In combination, a rotary fan positioned to produce a current of air having a generally upward movement, a single windstream control member positioned axially within said current to minimize horizontal currents of air normally produced by said fan, and an air purifier comprising an electric discharge device positioned to contact said air between said fan and said control member.

50 11. An air moving mechanism comprising a rotary fan having horizontally disposed blades and an air deflector spaced apart therefrom, said air deflector having an external surface presented toward said fan and being curved outwardly from said fan near its widest diameter and inwardly toward the axis of said fan from its widest diameter to the point in its contour farthest away from said fan.

55 12. An air moving mechanism comprising a rotary fan having horizontally disposed blades and an air deflector spaced apart therefrom, said air deflector having an external surface presented toward said fan and being curved outwardly from said fan near its widest diameter and inwardly toward the axis of said fan from its widest diameter to the point in its contour farthest away from said fan, said inward curves meeting at a point farthest from said fan.

ROBERT JOHN.
